CLAIM

The ornamental design for a combined utensil rest and card holder, as shown and described.

DESCRIPTION

FIG. 1 is a front perspective view of the combined utensil rest and card holder showing our new design;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a right side elevational view thereof, the left side elevational view being an identical mirror image thereof.
